[57] CLAIM

The ornamental design for a ring and thimble holder,
substantially as shown and described.

DESCRIPTION

FIG. 1 is a front elevational view of the ring and thimble holder showing my new design;

FIG. 2 is a side elevational view from the right side of
FIG. 1, the other side being a mirror image thereof;

FIG. 3 is a top plan view; and

FIG. 4 is a section along line 4—4 of FIG. 1.

Fig. 1.

Fig. 2.

Fig. 3.

Fig. 4.
